UNITED STATES PATENT OFFICE

2,630,055

CONTROL APPARATUS

Charles H. Priesmeyer, Park Ridge, Ill., assignor
to Minneapolis-Honeywell Regulator Company,
Minneapolis, Minn., a corporation of Delaware

Application July 23, 1948, Serial No. 40,313

11 Claims. (Cl. 98—41)

1

The present invention relates to a slidable adjusting knob assembly for an air outlet register. Air outlet registers have in the past used a projecting lever for operating their damper blades but this construction is relatively unsightly and the projecting lever is a potential cause of minor accidents. Use of a slidable adjusting knob movable over a portion of the front face is complicated by the requirement that there must be no noticeable rubbing of painted surfaces of the register even after several repaintings of the guide. It is thus an object of this invention to provide an improved adjusting handle for an air outlet register.

It is a further object to provide a slidable knob arrangement for a register which is easily attached, attractive in appearance and does not project unduly from the front of the register.

It is an additional object to provide an adjusting knob assembly arranged to minimize injury to adjacent painted surface.

It is a somewhat similar object to provide an adjusting knob slidable along a slotted member and guided so that contact with the member on the exposed side is only along the slot forming edges of the member.

It is also an object to provide a slide knob arrangement that can be used with a register adjusting lever with a minimum of change of the lever.

It is a further object to provide an adjusting knob arrangement that is economical to manufacture and easy to assemble.

These and other objects will become apparent upon a study of the following specification and drawings wherein:

Figure 1 is a partial front elevation of a register with an adjusting knob for its damper blade.

Figure 2 is a sectional view taken on the line 2—2 of Figure 1.

Figure 3 is a sectional view, enlarged, taken on the line 3—3 of Figure 1.

Figure 4 is an elevation view of the back side of the knob of Figures 1 to 3.

Figure 5 is a front elevation view of the clip of Figures 1 to 3.

Figure 6 is a fragmentary view similar to Figure 3 showing a modified attachment between the clip and the knob.

Figure 7 is an end view of the knob of Figure 6.

Figure 8 is a partial sectional view similar to Figure 2 showing a modified knob and clip assembly.

Figure 9 is an elevation view of the clip used in Figure 8.

The present knob arrangement, while applicable to registers of various types and construction, is especially intended for those of the sort disclosed and claimed in the copending applica-

tion of Hermanson et al., Serial No. 656,274, filed March 22, 1946.

In Figures 1 and 2, such a register is shown in part and comprises a grill portion 10 including diffuser blades 11, damper blades 12 and 13, a linkage 14 for simultaneously operating the blades, and a pivoted lever 15 for operating said linkage. As disclosed in the above cited application, and as used in practice prior to this invention, lever 15 was made sufficiently long to extend through slot 16 in channel member 17 and thus form an operating handle, member 17 being part of the front face of the register. Linkage 14 comprises, in addition to link 15, a link 61 rigidly attached to blade 12 and a link 62 pivotally attached to blade 13 and pivoted to link 61 at 63, pivot 63 being located about $\frac{1}{3}$ the length of pivot 61 from its free end. A short link 64 is pivotally attached at 65 to the end of link 61, with its other end being pivotally connected to the end of link 15 at 66. Link 15 is pivotally attached to link 62 at 67, pivot 67 being relatively near the end of link 15 and in the upper portion of link 62. This arrangement forms, in effect, a partial toggle linkage comprising the end portion of link 15 and link 64 which, in adjusting the distance between pivots 65 and 67 adjusts the angular relation of links 61 and 62 and thus the opening of the damper blades 12 and 13. The adjustment of the toggle linkage is effected by the remaining or lever portion of link 15, the linkage being such that movement of link 15 in a direction to reduce the distance between pivots 65 and 67 tends to open the blades whereas a reverse movement tending to lengthen the distance between said pivots adjusts the blades to a closed position, friction tending to hold the parts in their adjusted relation.

As shown in Figure 2, lever 15 is cut off in back of member 17 and fits loosely in a hole or slot 19 in the back side or base portion 20 of a clip or slide member 21. Sides 23 of said member are bent at right angles to base 20 and, spaced from 20, upper and lower pairs of in-turned guide tongues 24 and 25 are bent from said sides 23, said tongues 24 and 25 lying in a plane substantially parallel to base portion 20. Tongues 24—25 are arranged to slide along the rear edges of the flanges 26 of channel member 17, as shown in Figures 1 to 3. Intermediate the upper and lower guide tongues of member 21, arms 30 extend outwardly from sides 23 in a straddling relation to member 17, member 21 being sufficiently wide that the distance between arms 30 is appreciably greater than the width of channel 17. For convenient attachment purposes, the outer ends of arms 30 are reduced somewhat in width and are preferably provided with rearwardly extending barbs, or the like, 31. An adjusting knob or handle 35 is arranged

in front of channel member 17 and is provided with spaced sockets or recesses 36 in which are inserted the barbed ends of arms 30, thereby securely attaching the knob 35 to member 21. To prevent knob 35 or arms 30 from rubbing against the exposed surfaces of member 17, a projecting longitudinally extending convex guide rib 38 is provided along the back side of 35 and, being wider than slot 16, engages only the slot forming edges of member 17. As further assurance that the knob will be accurately guided even if the arms 30 should loosen somewhat, rib 38 is preferably surmounted, in effect, by a fin or rib 39 having parallel sides and formed integral with rib 38. Obviously, fin 39 is somewhat narrower than slot 16 and, because it extends through slot 16, is particularly useful in preventing twisting movements of said knob.

With knob 35 and slide member 21 assembled as described above, and lever 15 projecting through opening 19, vertical movements of knob 35 will cause lever 15 to operate dampers 12 and 13 through linkage 14. Because of the loose fit of lever 15 in hole 19 and the spacing of portion 20 from tongues 24-25, and thus from channel member 17, the distance between member 17 and the end of lever 15 is permitted to vary appreciably without interfering with the purely vertical movements of knob 35. As the only contact between knob 35 and member 21 with member 17 is between tongues 24-25 and the rear edges of flanges 26 and between rib 38, and possibly fin 39, and the slot forming edges of 17, it is apparent that the exposed painted surfaces of member 17, with the exception of the edges along slot 16, are protected from rubbing and may, if desired, be repainted several times without interfering with the operation of the present apparatus.

While the barbed arrangement for the ends of arms 30 is considered a preferred construction, a modified knob 43, similar to 35, may have oppositely arranged sockets 41 and 42 formed in its sides, as shown in Figures 6 and 7, to receive in-turned ends 44 and 45, respectively, or arms 46, with recesses 47 being formed to receive the adjacent portions of said arms. Except for the knob attaching portion, arms 46 correspond to 30 in the example above.

In addition, as a further modification, knob 51 in Figure 8, generally similar to knobs 35 and 43, has spaced rearwardly extending arms 52 molded in said knob, the free ends of said arms having rectangular holes 53 for interlocking with oppositely disposed tongues 54 of slide member 55. Member 55, best shown in Figure 9, is essentially the same as 21 previously described excepting that tongues 54 are formed in the same plane as the base portion of the member and no arms corresponding to 30 or 46 are provided for said member, the connecting arms, as above mentioned, being formed as part of its associated knob 51.

As a study of the above disclosure may suggest other substitutions and equivalent constructions, the scope of this invention is to be determined only by the appended claims.

I claim as my invention:

1. In a register having adjustable damper means, a movable lever for operating said damper means, a channel member arranged in front of said damper means and having its flanges directed toward said damper means, a longitudinal slot in said member, said member being arranged parallel to the plane of movement of said lever, a clip member, means operatively connect-

ing said clip member to said lever, said clip member having inturned tongues slidable along the edges of the flanges of said channel member, said clip member having spaced arms extending outwardly past said channel member on opposite sides thereof, and a knob attached to said arms and arranged on the front side of said member, said knob including a projecting generally convex guide rib of greater width than the slot in said member and slidable along the edges of said slot for spacing the rest of said knob from said member and for preventing said arms from engaging said channel member.

2. In a register including adjustable damper means and having a front face portion, a relatively narrow elongated slotted member arranged in said face portion, said slotted member having front and rear portions, an adjusting knob having rearwardly extending guide means movable along said slot and of such size and shape as to contact said member only along the edges of said slot, a rear slide member having slide portions facing said knob and engageable with spaced rear portions of said slotted member spaced by said slot, spaced relatively rigid connecting means arranged in straddling relation to said slotted member and connecting said knob to said slide member, said connecting means being spaced sufficiently to avoid rubbing on said elongated slotted member, and means for operatively connecting said slide member to said damper means.

3. In a register having a front face portion and including adjustable damper means, an elongated relatively narrow slotted member arranged in said face portion, an operating lever for said damper means movable in a plane parallel to the slot in said slotted member, a slider member, means operatively connecting said slider member to said lever, said slider member being movable along the back side of said slotted member, an adjusting knob having a fixedly related generally convex rib portion movable along the front side of said slotted member, said rib portion extending into said slot and engaging the slot defining edges of said member, the knob otherwise being spaced from said slotted member by said rib portion, and a pair of relatively rigid connecting members for connecting said slide member to said knob, said arm members being spaced from said slotted member by more than the width of said member and prevented from rubbing against said member by the guiding effect of the rib portion of said knob.

4. A knob assembly for use with a device having an elongated relatively narrow member with a longitudinal slot, said member being located in a position on said device where it is plainly visible and readily accessible, said device also including an operating member movable in approximate alignment with said slot, said knob assembly comprising, in combination, a rectangular slide member having a back side portion, means for connecting said back side portion to said movable member, upper and lower pairs of in-turned tongue members connected to said back side portion and arranged in a plane parallel to and spaced from said back side portion, a pair of arm members connected to the opposite sides of said slide member intermediate the upper and lower tongue members and extending perpendicularly away from said back side portion, the outer ends of said arm members having rearwardly directed barb means, and an adjusting knob having spaced socket portions inserted over said arm members and held in place by said barb means,

said knob including a projecting guide means arranged to bear against the slot forming edges only of said narrow slotted member, said guide means being formed between said socket portions and extending lengthwise of said slide member.

5. A knob assembly for use with a device having an elongated exposed member with a longitudinal slot and having a member movable in approximate alignment with said slot comprising, in combination, a rectangular slide member having a back side portion, means for operatively connecting said back side portion to such a movable member, upper and lower pairs in inturned tongue members connected to said portion and arranged in a plane parallel to and spaced from said back side portion, a pair of arm members connected to the opposite sides of said slide member intermediate the upper and lower tongue members and extending perpendicularly away from said back side portion, inturned tongues on the outer ends of said arm members, and an adjusting knob having oppositely disposed sockets for receiving said tongues for thereby securing said knob to said slide member, said knob having a rearwardly projecting convex guide rib arranged to coat with the slot forming edges of said elongated exposed member.

6. A knob assembly for use with a device having an elongated exposed member with a longitudinal slot and having a member movable in approximate alignment with said slot comprising, in combination, a rectangular slide member having a back side portion, means for operatively connecting said back side portion to said movable member, upper and lower pairs of inturned tongue members connected to said portion and arranged in a plane parallel to and spaced from said back side, a pair of oppositely disposed tongue members in the plane of said back side portion and arranged between the upper and lower inturned tongues, and an adjusting knob having spaced rearwardly extending arm members each having a recess for coating with its respective oppositely disposed tongue, said knob having a rearwardly projecting convex guide rib arranged to slide along the slot forming edges of said elongated exposed member and to space the other portions of said knob from said member.

7. A knob assembly for use with a device having an elongated relatively narrow member exposed to view and manually accessible, said narrow member having a front side and a back side and having a longitudinal slot, said device having a member movable in approximate alignment with said slot, said knob assembly comprising, in combination, a rectangular slide member having a base portion, said member including upper and lower slide portions adapted to engage the back side of said exposed member, means for operatively connecting said base portion to said movable member, an adjusting knob having an integral generally convex rearwardly projecting guide rib arranged to slide along said slot and to space said knob from the front side of said exposed member, and spaced connecting means arranged in straddling relation to said elongated member for connecting said knob to said slide member, said connecting means being spaced apart more than the width of said narrow member.

8. In a device having an exposed and manually accessible relatively narrow slotted face member with front and back sides, an adjusting knob arranged in front of said member and having guide means movable along the slot in said

member, said guide means being generally convex in section and of greater width than said slot and engaging said member only along the edges of said slot, a rear slide member having forward

5 facing slide portions engageable with the rear portions of said face member and movable along the back side of said member, and spaced connecting means arranged in straddling relation to said slotted face member and firmly connecting said adjusting knob to said slide member.

9. In a register including adjustable damper means and having a relatively narrow slotted member exposed to view and manually accessible, an operating lever for said damper means movable in a path substantially parallel to the slot in said member, a slider member, means operatively connecting said slider member to said operating lever, said slider member being movable along the back side of said slotted member, and an adjusting knob fixedly attached to said slider member, said knob having convex guide means on its back side for engaging only the slot forming edges of said slotted member, said guide means being wider than said slot so that said knob is spaced from the surfaces of said slotted member by said guide means.

10. In a register including adjustable damper means and an operating lever therefor, an exposed and manually accessible register face member having a slot substantially in alignment with the path of movement of said lever, a clip member having means for connecting said clip member to said lever and movable along the back side of said exposed member, an adjusting knob movable along the exposed face of said register member, and rigid connecting means connecting said knob to said clip member, said knob including convex guide means for engaging only the slot forming edges of said register member, said guide means spacing other parts of said knob from said exposed member.

11. In a device including a movable member and an operating lever therefor, a longitudinally extending relatively narrow exposed and manually accessible member of said device having a front side and a back side and having a slot substantially parallel with the path of movement of said lever, a clip member having means for operatively connecting said clip member to said lever and movable along the back side of said member, a knob movable along the front side of said member for moving said clip member, and spaced arms attached to and extending from said clip member for straddling said exposed member and attaching said knob to said clip member, said knob including a fixedly related rearwardly extending longitudinal guide rib movable along said slot, said rib being convex in section and of a size sufficient for spacing said knob from said exposed member, said arms being sufficiently spaced and so guided by said rib that they avoid contacting said narrow slotted member.
